UNITED STATES PATENT OFFICE.

EDWARD L. TORSCH AND JAMES R. LEE, OF BALTIMORE, MARYLAND.

BADGE.

SPECIFICATION forming part of Letters Patent No. 337,717, dated March 9, 1886.

Application filed August 24, 1885. Serial No. 175,167. (No model.)

To all whom it may concern:

Be it known that we, EDWARD L. TORSCH and JAMES R. LEE, of the city of Baltimore and State of Maryland, have invented certain 5 Improvements in Badges, of which the following is a specification.

This invention relates to certain improvements in the holder whereby the badge is secured to the coat of the wearer, as will herein- 10 to after fully appear.

In the drawings forming a part hereof, Figure I is a front view of a badge of the description to which the improved holder is adapted for application. Fig. II is a rear view of the 15 badge and the holder. Fig. III is a sectional view of the badge, taken on the dotted line xx , Fig. II. Fig. IV is a rear view of the improved holder before its application to the badge. Figs. V, VI, and VII illustrate modifications in the construction of the holder, as 20 hereinafter specified.

A is the badge, and B the holder, which consists of the pin a and bar b , the latter having the points c , which project beyond its edge, 25 and are passed through the badge and duplicated to form a complete fastening.

In Figs. II and III the badge is folded over the bar b , and the pin a is passed through the folded end of the badge. The clasping-points c in these figures are on the lower edge only of 30 the bar b , and are folded over the edge of the badge.

In Fig. IV the clasps are shown as extended.

In Figs. V, VI, and VII the bar b is placed in front of the badge instead of in the rear, and 35 a greater number of pointed clasps are employed. If desired, the upper edge of the bar may be turned over the end of the badge, so as to give a better finish.

We claim as our invention— 40

In combination with the badge A, the bar b , having the pin a and points c , which points project from the edge of the bar, and are passed through the said badge and folded to form a complete fastening, substantially as specified. 45

E. L. TORSCH.
JAMES R. LEE.
